UNITED STATES PATENT OFFICE.

GEORGE C. GEBELEIN, OF WELLESLEY, MASSACHUSETTS.

PLATE.

Application filed September 22, 1924. Serial No. 738,978.

To all whom it may concern:

Be it known that I, GEORGE C. GEBELEIN, a citizen of the United States, residing at Wellesley, in the county of Norfolk and State of Massachusetts, have invented certain new and useful Improvements in Plates; and I do hereby declare the following to be a full, clear, and exact description of the invention, such as will enable others skilled in the art to which it appertains to make and use the same.

The present invention relates to plates or trays and more particularly to an article of this character which is provided with means for retaining and holding a liquid receptacle.

The object of the present invention is to provide a new and improved form of plate which will adequately serve food and liquid at luncheon parties, teas, picnics and similar gatherings.

With this object in view, the various features of the invention consist in certain novel features of construction, combinations and arrangements of parts hereinafter described and claimed, the advantages of which will be obvious to those skilled in the art from the following description.

In the accompanying drawings illustrating the preferred form of the invention Fig. 1 is a section in elevation of the improved plate with a cup of conventional form supported thereon; Fig. 2 represents a section in elevation of several plates stacked one upon another and illustrating the manner in which the plates nest; and Fig. 3 is a plan view of the plate showing the preferred location of the cup retaining lip within the plate.

The plate shown in the illustrated embodiment of the invention is preferably molded or drawn into a circular form, as indicated at 10 in Fig. 3. The plate is provided with a flat bottom portion 12 rounded by a rim 14, the walls of the bottom portion and rim being of uniform thickness. Located at one side of the plate and within the upstanding rim 14 is an annular lip 16 raised from the bottom portion 12 and of sufficient depth to retain a cup or other liquid receptacle, even though the plate may be substantially inclined or tipped from the horizontal. The annular lip 16 is provided with converging walls 18 and 19 which surround a flat bottom portion 20 positioned

substantially at the level of the bottom portion 12. The formation of the annular lip with converging walls provides an annular recess or depression 22 upon the underside of the plate which permits nesting of a second plate therein, as will be evident from an inspection of Fig. 2.

The provision of the cup retaining depression of substantial depth in the manner indicated not only serves to firmly hold the cup or liquid receptacle in proper position on the plate but prevents contact between the sides of the cup and food supported upon the plate, such as sandwiches with soft fillings. It will be evident from an inspection of the drawings that the annular lip is spaced well within the surrounding rim of the plate so that the latter may be grasped and supported at any point without contact of the fingers with the cup. This location of the recess leaves a maximum portion of the plate available for the use of food but permits a cup containing hot liquid to be supported without danger or liability of contact by the person holding the plate.

A plate of this character may be made of metal suitably drawn or molded to form the plate with the cup retaining lip raised from the bottom portion or it may be molded with the lip therein from paper, fibre composition, or similar material. The formation of a relatively deep annular lip in the manner illustrated is especially advantageous in connection with paper or composition plates, as it materially strengthens and reinforces the plate against distortion and enables it to support heavier burdens than would otherwise be possible. It will be evident that, irrespective of the material employed, the formation of the cup holding depression permits the plates to be nested and stacked, this feature being of especial advantage in connection with plates employed for picnics and similar gatherings, where it is desirable to stack large numbers of plates in as small a space as possible.

Although the present invention has been described in connection with a plate of conventional circular form, nevertheless it should be understood that the features of the invention are equally well applicable to what might be termed a tray or similar article of manufacture produced in any conventional form. It is accordingly intended that the term "plate" as employed through-

out the specification and claim shall define any article adapted for supporting food and liquid.

I claim:

An article of manufacture comprising a plate having a relatively flat bottom portion of uniform thickness surrounded by a retaining rim, and an annular retaining lip raised from the flat bottom portion at one side thereof and within the rim, the annular lip being formed with converging walls to

provide a retaining recess of substantial depth for the retention of the base of a liquid receptacle and form on the opposite side an annular recess of sufficient depth and width to permit introduction of the retaining lip on a second plate and substantial nesting of two or more plates one within another. ¹⁵

In testimony whereof I have signed my name to this specification.

GEORGE C. GEBELEIN.
